UNITED STATES PATENT OFFICE.

RALPH C. SEYMOUR, OF LARCHMONT, NEW YORK, ASSIGNOR TO GOSS PRINTING PRESS COMPANY, OF CHICAGO, ILLINOIS, A CORPORATION OF ILLINOIS.

SHEET-HANDLING MACHINE.

1,165,911.

Specification of Letters Patent. Patented Dec. 28, 1915.

Application filed August 30, 1909. Serial No. 515,268.

To all whom it may concern:

Be it known that I, RALPH C. SEYMOUR, a citizen of the United States, residing at Larchmont, in the county of Westchester and State of New York, have invented new and useful Improvements in Sheet-Handling Machines, of which the following is a specification.

The invention relates to sheet handling machinery, and more particularly to machines for severing a sheet and feeding off the two parts either separately or associated.

Objects of the invention are to provide a machine for handling sheets in a manner corresponding to the arrangement of plates on the press; to provide for feeding off the severed portions of the sheet *seriatim* when the sheets are imprinted with duplicate matter on each of the severed parts thereof; and to provide for associating the severed parts of the sheets and feeding them off together when the matter is not so duplicated; to provide for reliable and automatic handling of the sheet in either of the ways indicated.

These and other objects of invention will in part be obvious and will in part more fully appear hereinafter.

The invention consists in the novel parts, arrangements, constructions, combinations and improvements herein shown and described.

The accompanying drawings, referred to herein and constituting a part hereof, illustrate one embodiment of the invention, and serve with the description to elucidate the principles of the invention.

Of the drawings: Figure 1 is a longitudinal section taken just within the machine frame, of a mechanism constructed in accordance with the principles of the invention: Fig. 2 is a fragmentary, diagrammatic, view of parts shown in Fig. 1 just after the severing of the sheet by the cutters; Fig. 3 is a view similar to Fig. 2 showing the rear portion of the sheet being fed up and associated with the forward portion; Fig. 4 shows the two portions of the sheet being fed off together after being associated; Fig.

5 is a similar view showing the front portion of the sheet being fed off and the rear portion being fed up to the front gage, preparatory to being fed off alone later; and Fig. 6 is a view of a leaf or vane cam, such as may be used to vary the timing of the machine parts; Fig. 7 is a view looking at Fig. 6 from the right.

Referring to the accompanying drawings, illustrating by way of example one embodiment of the invention, a suitable sheet supply is shown, indicated generally by the reference numeral 1. As shown, said sheet supply consists of a sheet feeder feeding from a stack, although the sheets might be fed in some other manner, as by being fed directly from the press either as sheets or as a severed web.

One of the uses for which the present machine is intended is to feed an insert into a book or magazine, and to feed in inserts of different sizes with equal facility. By way of example, where the invention is applied to, or associated with, machines for making a book or magazine in which the sheets are four page sheets and receive one fold along the back of the book which is also stitched, either a four or an eight page insert may be run in the machine. It will be understood, of course, that the foregoing relates to the machine longitudinally, as obviously the book might be duplicated a number of times transversely and slitters might be used to separate them. With the four-page insert, the forms would be put on the press in duplicate in fours, while with the eight page insert the forms would be put on in eights single. With the machine shown and described, when the four-page insert is run, the sheet is severed and run off one part to one book or magazine, and the second part to the next succeeding book or magazine. When the eight-page insert is run, the necessity arises of associating the second four with the first four, the associated sheets then being fed off to each book or magazine in succession.

It will be understood that the foregoing is illustrative of a use of the present inven-

tion and is not restrictive either as to the scope of the invention or as to the different ways in which it may be used, as it may obviously be used in other ways.

5 Means are provided by the invention for arresting the fed sheet and for severing it into a plurality of parts. Means are also provided, coöoperating with the means just indicated, for feeding off the severed portions singly, that is, one after the other, or for superimposing them and then feeding off the associated sheets together. In the embodied form of these several means, a stop for arresting, positioning and controlling the front portion of the sheet is shown herein as a front gage 2, pivotally supported at 3, and having connected therewith an arm 4. The form of actuating means for said gage shown herein comprises a link 5 pivoted to said arm 4 and to a suitable bent lever 6. There is shown pivoted to the lever 6 a rod 7 straddling by means of a suitable yoke, a shaft 8, said rod 7 being in operative relation with a cam 9 by suitable means, such as the roll 10. Means are likewise shown for arresting and controlling the rearmost portion of the sheet, the illustrated form thereof comprising a tail stop or clamping finger 13 mounted on shaft 14, said shaft having connected therewith an arm 15. Pivoted to said arm 15 is shown a rod 16, straddling by a suitable yoke 17 the shaft 8. The cam 18 is shown acting on the rod 16 through the cam roll 19.

35 Sheet severing means are provided, and the illustrated form thereof comprises opposed knives 24 and 25. The knife 24 is shown carried in fixed bearings 26 on the machine frame. The knife 25 is shown reciprocating to and from the knife 24, and for this purpose is shown mounted in a frame 27 working in suitable guides in the machine frame. Means for actuating said knife are provided, and the form thereof shown herein comprises a cam 28 on the shaft 29, the frame 27 having a roll 30 in coöoperative relation with said cam. Means are also provided in the present embodiment for causing the contiguous ends of the 40 two severed portions of the sheet to pass out of alinement with each other, in order that one portion may be fed forward into superimposition with respect to the other portion, so that the thus associated sheets 45 may be fed off together. In the present embodiment the sheets are also fed along a substantially straight path. In the present embodiment, furthermore, the contiguous ends of the sheet pass out of alinement by 50 the tail of the forward portion of the sheet being permitted to drop below the level of the path of the sheets. The sheets are supported at their forward end upon bars 35, said bars being shown deflected or slanted

55 downwardly at the knife 24, thus permitting the tail of the forward portion of the sheet to drop as soon as it is severed by the knives 24 and 25, as shown at *a* in Fig. 2. Suitable bars 36 are shown for supporting the rear end or portion of the sheet.

70 Suitable progressing means for the entire sheet and for each portion of the sheet are provided, and the embodied form of such means comprises tapes 37 engaging the sheets beneath and tapes 38 engaging the sheets above. The tapes 37 are shown supported on suitable rollers 39 and 40. The tapes 38 are shown passing over rollers 41 at the end nearer the sheet feeder, or other source of supply, and around rolls 42 at the end toward the cutters 24 and 25. The rollers 42 are drop rollers and are shown mounted upon arms 44. The arms 44 are shown connected to shaft 14 to give the desired motion to the rollers 42. A drop roller 43 is also shown for feeding the sheets in between the tapes 37 and 38. Suitable means for raising and dropping the rollers 43, and for doing it in proper relation to the operation of the other parts are provided. No mechanism for doing this is shown, however, as it may be effected in any well known manner, as by means of a suitable cam and lever movement.

90 Suitable means are provided for feeding off the sheets from the front stop 2, and the illustrated form thereof comprises tapes 50 working over rollers 51, 52 and 53. A suitable series of drop rollers 54 mounted upon arms 55 may also be provided as part of the feeding off means. The arms 55 are shown herein fixed to move with the bent levers 6, for convenience, for the purpose of moving them into and out of feeding position, the rollers 54 in this case actually moving against the sheet from beneath. Coöperating with the tapes 50 are shown a series of tapes 56 working over rolls 57, 58 and 59.

95 The insert is associated with its book in a suitable manner, and in the present embodiment the group of sheets is fed to, or collected upon a three-way cylinder 65, although other associating means might be employed as found convenient or desirable, so far as concerns many features of the invention. The sheet bundle, which may also have had the cover previously associated with it, and the insert may then be run off together by the tapes 66 toward the stitchers, slitters, or folders, or any other mechanism for operating on or receiving the same. Stripers 69 may be utilized, if desired, to insure the sheets being taken from the cylinder 65 and fed into the tapes 66 and 67. Suitable means may also be provided for bringing the sheet bundle and insert into exact register, and herein there is shown for this purpose a stop gate 68, which may be

100 105 110 115 120 125

conveniently located with respect to a slitting, stitching, or other mechanism, as desired.

The manner of operation of the herein described mechanism, is substantially as follows: We may consider first the case where the two portions of the sheet are superimposed before being fed off. The sheet is fed up from the source of supply, by the 10 rollers and tapes, as already described, until it is brought to rest against the front gage 2. The tail stops 13 move into engagement with and clamp the rear end of the sheet firmly in position. The knives 24 and 25 then act to sever the positioned and held sheet into two parts, as shown in Fig. 2. The tail end of the forward portion of the sheet will then drop out of alinement with the general plane of the sheet, as already 20 explained, and as shown at *x* in Fig. 2. The tail stops 13 are now raised, and the drop rollers 42 serve to feed the rear portion of the sheet forward, as shown in Fig. 3, so that said rear portion is superimposed upon 25 and associated with the forward portion of the sheet. The front gage 2 is then raised, and the roller 54 moved into engaging position and the associated sheets fed off together, as shown in Fig. 4, to become associated with the sheets from the cylinder 65.

When the two portions of the sheet are to be fed off separately, for instance, when they are duplicates of each other, the sheet is advanced as before and brought to rest 35 by the front gage and is severed into two portions as before by the cutters 24 and 25, the parts being in this instance also as shown in Fig. 2 of the drawings. The machine parts are now timed so that the tail stops 40 13 remain in engagement with the rear portion of the sheet, while the front gage 2 is raised, and the rollers 54 correspondingly moved, thus permitting the front portion of the sheet to be fed off in order to be associated with the sheets from the cylinder 65. The front gage 2 now descends again, the tail stop 13 is raised, the drop rollers 42 are dropped, and the rear portion of the sheet is fed forward to the front gages 2. 50 These are then raised to permit the feeding off of the rear portion in turn so that it may be associated with the sheets from the cylinder 65.

The requisite timing of the parts, or 55 changes in such timing, may be secured in any desired manner, as by shifting the cams 8 and 19 on their shaft, or in any other suitable way. This may be done by providing said cams with leaves or vanes 73, which 60 may be held in adjusted position by a nut 74, in a well known manner.

The invention in its broader aspects is not limited to the particular forms of construction herein shown, nor to any particular

forms of construction, but changes may be 85 wrought therein without departing from the principles of the invention and without sacrificing its chief advantages.

What I claim as my invention, and desire to secure by Letters Patent, is:

1. A sheet handling machine including in combination a front gage, means for feeding a sheet to register with said gage, means for severing the sheet while registered to the gage into a plurality of parts, means for 75 superimposing a plurality of said parts in registry at the front gage before they are fed off and means for feeding off said superimposed parts unfolded.

2. A sheet handling machine including in combination means for feeding a sheet, means for arresting the sheet, means for severing the arrested sheet into a plurality of parts, means for moving one of said parts into superimposition upon another of said 85 parts while said latter part is still so arrested, and means for feeding off said superimposed parts together unfolded.

3. A sheet handling machine including in combination means for feeding a sheet, 90 means for engaging a sheet at its front edge to bring it to rest, means for severing the sheet into two parts, means for feeding forward the rear portion of the sheet while the front portion is still at rest against the gage, 95 means for causing the contiguous ends of the two portions to pass out of alinement so that as the rear portion is fed forward one of said two portions will be superimposed upon the other and means for feeding off 100 said superimposed parts unfolded.

4. A sheet handling machine including in combination means for feeding a sheet, means for arresting the sheet, means for severing the sheet transversely to the direction of feed into a plurality of portions, means for deflecting the rear edge of the forward portion, means for feeding forward a rear portion into superimposition with said forward portion while it is still at rest 110 and means for feeding off said superimposed parts unfolded.

5. A sheet handling machine including in combination means for feeding a sheet, means for severing the sheet into a plurality of parts, and means for varying the speed of the severed parts of said sheet so as to cause them to feed off unfolded one after another or to feed off unfolded together in superimposition.

6. A sheet handling machine including in combination means for feeding a sheet along a substantially straight path, means for arresting the sheet in said path, means for severing said sheet while so arrested into a 125 plurality of parts, means for causing the adjacent edges of two adjacent portions of the sheet to pass out of alinement with each

other, and means for moving one of said portions substantially in said straight path into superimposition with another portion and means for feeding off said superimposed parts unfolded together.

7. A sheet handling machine including in combination means for feeding a sheet, means for engaging the sheet near one end to arrest it, means for engaging the sheet 10 near the other end to arrest it, means for severing said sheet between said two arresting means, means for causing one arresting means to cease to act upon the sheet while the other remains acting, and means for 15 moving the portion of the sheet released by its arresting means.

8. A sheet handling machine including in combination means for feeding a sheet, means for engaging the sheet near one end 20 to arrest it, means for engaging the sheet near the other end to arrest it, means for severing said sheet between said two arresting means, means for causing the foremost arresting means to release its portion of the sheet and to arrest the next succeeding portion, means for feeding off said first-mentioned portion, means for causing the rearmost arresting means to release its portion, and means for feeding said rearmost portion 30 to said foremost arresting means to be arrested thereby.

9. A sheet handling machine including in combination means for feeding a sheet, means for engaging the sheet near one end 35 to arrest it, means for engaging the sheet near the other end to arrest it, means for severing said sheet between said two arresting means, means for causing the rearmost arresting means to release its portion, means 40 for feeding said rearmost portion forward to associate it with the foremost portion, and means for feeding off the associated portions together.

10. A sheet handling machine including 45 in combination means for feeding a sheet, means for engaging the sheet near one end to arrest it, means for engaging the sheet near the other end to arrest it, means for severing said sheet between said two arresting means, means for causing the rearmost 50 arresting means to release its portion, means for feeding said rearmost portion forward to associate it with the foremost portion, and means for feeding off the associated portions 55 together.

11. A sheet handling machine including in combination a front gage, a tail stop and a transverse sheet cutter therebetween for cutting the sheet transversely and parallel 60 to the edge registered by said front gage while it is arrested by the front gage and tail stop.

12. A sheet handling machine including in combination a front gage, a tail stop, a

sheet cutter located intermediately said 65 gage and tail stop, and a drop roller located between said tail stop and sheet cutter.

13. A sheet handling machine including in combination a source of sheet supply, a drop roller for conveying a sheet therefrom, 70 a front gage, a sheet cutter and a tail stop located within a sheet length of each other, and to one side of said drop roller, and a drop roller located between said tail stop and said sheet cutter. 75

14. A sheet handling machine including in combination a front gage, a sheet cutter for cutting a sheet transversely when registered to said gage, a support for the sheet between said gage and said cutter which 80 permits the part near the severed end of the sheet to drop, and means for feeding up the other portion of the sheet from beyond the cutter into superimposition with the portion between the gage and cutter and 85 into registry with said gage, and means for feeding off said superimposed parts unfolded and registered.

15. A sheet handling machine including in combination a front gage, a tail stop, a 90 sheet cutter located intermediately said gage and stop, said devices being arranged to all operate upon the sheet at one time, means for raising the front gage, means for raising the tail stop, said two means being 95 arranged so that either may release its portion of the sheet while the other is still in engagement with its portion.

16. A sheet handling machine including in combination a front gage, a tail stop, a 100 sheet cutter located intermediately said gage and stop, said devices being arranged to all operate upon a sheet at one time, means for raising the tail stop while the front gage is still engaging the sheet, and 105 means for then raising the front gage.

17. A sheet handling machine including in combination a front gage, a tail stop, a sheet cutter located intermediately said gage and stop, said devices being arranged to all 110 operate upon a sheet at one time, means for raising the front gage while the tail stop is still engaging the sheet and means for then raising the tail stop.

18. A sheet handling machine including 115 in combination a front gage, a sheet cutter, a support for the sheet between said gage and cutter which permits the severed end of the sheet to drop, a tail stop and sheet progressing means for engaging the sheet on the 120 opposite side of the cutter from said front gage and said support.

19. A sheet handling machine including in combination means for associating a plurality of sheets, means for feeding the associated sheets to a registering device, means for cutting a sheet and superimposing the parts together, and means for feeding said

superimposed parts to said registering device whereby said associated sheets and said superimposed parts of the severed sheet are registered with respect to each other by said 5 registering device.

20. A sheet handling machine including in combination a collecting cylinder for associating sheets, means for progressing the associated sheets from said cylinder to a 10 registering stop, means for cutting a sheet and superimposing the cut parts, and means for feeding said cut and superimposed parts to said registering stop, whereby said associated sheets and said superimposed parts 15 of the severed sheet are registered with respect to each other by said registering stop.

21. A sheet handling machine including in combination a mechanism for associating sheets, means for progressing the associated 20 sheets from said associating mechanism to a registering stop, means for cutting a sheet and superimposing the cut parts, and means for feeding said cut and superimposed parts to said registering stop, whereby said associated sheets and said superimposed parts 25 of the severed sheet are registered with respect to each other by said registering stop.

22. A sheet handling machine including in combination means for feeding a sheet, 30 means for arresting the sheet, means for severing the arrested sheet transversely to the direction of feed into a plurality of portions, means for deflecting the rear edge of the forward portion while so arrested relatively to the remainder of said portion, means for feeding forward a rear portion into superimposition with said forward portion while it is still at rest and means for feeding off said superimposed parts 35 unfolded.

23. A sheet handling machine including in combination a front gage, means for feeding a sheet to said gage, means for severing the sheet while stopped and registered by 45 said gage into a plurality of parts, means for superimposing a plurality of said parts at the front gage before they are fed off, and means for feeding off said superimposed parts in the plane of said sheets.

50 24. A sheet handling machine including in combination a front gage, means for feeding a sheet to said gage, means for severing the sheet into a plurality of parts, means for superimposing a plurality of said parts at 55 the front gage before they are fed off, and means for feeding off the superimposed parts in the same direction as they were fed.

25. A sheet handling machine including in combination means for feeding a sheet, 60 means for engaging a sheet at its front edge to bring it to rest, means for severing the sheet into two parts while so at rest, means passing into engagement with the severed rear portion of the sheet to progress it into

superimposition with the front portion while 65 said front portion is still at rest against the gage, and means for causing the contiguous ends of the two portions to pass out of alignment so that as the rear portion is fed forward one of said two portions will be superimposed upon the other. 70

26. A sheet handling machine including in combination means for feeding a sheet, means for engaging the sheet at its front end to arrest the sheet, means for severing the 75 sheet, means for arresting and releasing the rear portion of the severed sheet, and means for forwarding the rear portion into superimposition with the forward portion while the forward portion is still arrested. 80

27. A sheet handling machine including in combination means for associating a plurality of sheets, means for cutting another sheet in two and superimposing the cut parts, means for directing said associated 85 sheets and said superimposed sheets into a horizontal pathway, whereby they become associated together, and a stop in said pathway for registering said sheets relatively to each other. 90

28. A sheet handling machine including in combination a front gage, means for feeding a sheet along a horizontal pathway to said gage, means for severing the arrested and registered sheet into a plurality of 95 parts, feeding off means, and means for superimposing a plurality of said parts at the front gage before they are fed off.

29. A sheet handling machine including in combination means for feeding a sheet 100 along a horizontal pathway, means for arresting the sheet in said horizontal pathway, means for severing the arrested sheet into a plurality of parts and means for moving one of said parts into superimposition upon 105 the other of said parts while said latter part is still so arrested.

30. A sheet handling machine including in combination means for feeding a sheet 110 along a horizontal pathway, means for engaging a sheet at its front edge to bring it to rest in said horizontal pathway, means for severing the arrested sheet into two parts, means for feeding forward the rear portion of the sheet while the front portion 115 is still at rest against the gage, and means for causing the contiguous ends of the two portions to pass out of alignment so that as the rear portion is fed forward one of said two portions will be superimposed upon the 120 other.

31. A sheet handling machine including in combination means for feeding a sheet along a horizontal pathway, means for severing the sheet into a plurality of parts, and means for varying the speed of the severed parts of said sheet along a horizontal pathway so as to cause them to feed off one after 125

another or to feed off together in superimposition.

32. A sheet handling machine including in combination means for associating a plurality of sheets, means for cutting another sheet in two and superimposing the cut parts, means for directing said associated sheets and said superimposed sheets into a pathway, whereby they become associated

together, and a stop in said pathway for registering said sheets relatively to each other.

In testimony whereof, I have signed my name to this specification, in the presence of two subscribing witnesses.

RALPH C. SEYMOUR.
